US00D954749S

(12) **United States Design Patent** (10) **Patent No.:** **US D954,749 S**
(45) **Date of Patent:** **** Jun. 14, 2022**

(54) **ELECTRONIC DEVICE**

(71) Applicant: **Amazon Technologies, Inc.**, Seattle, WA (US)

(72) Inventors: **Jesse Wheeler Moore**, Oakland, CA (US); **Giles David Matthew McWilliam**, San Francisco, CA (US)

(73) Assignee: **Amazon Technologies, Inc.**, Seattle, WA (US)

(**) Term: **15 Years**

(21) Appl. No.: **29/806,025**

(22) Filed: **Aug. 31, 2021**

Related U.S. Application Data

(62) Division of application No. 29/684,862, filed on Mar. 25, 2019, now Pat. No. Des. 931,902.

(51) **LOC (13) Cl.** **14-03**

(52) **U.S. Cl.**

USPC **D14/496**; D14/203.7

(57) **CLAIM**

The ornamental design for an electronic device, as shown and described.

DESCRIPTION

FIG. 1 is a front, top, right perspective view of an electronic device;

FIG. 2 is a front view thereof;

FIG. 3 is a back view thereof;

FIG. 4 is a left-side view thereof;

FIG. 5 is a right-side view thereof;

FIG. 6 is a top view thereof; and,

FIG. 7 is a bottom view thereof.

The broken lines depict portions of the electronic device that form no part of the claimed design.

1 Claim, 7 Drawing Sheets
